UNITED STATES PATENT OFFICE.

CHARLES E. WAREAM, OF NORWOOD, OHIO.

POWER ATTACHMENT FOR PRESSING MACHINES.

Application filed January 2, 1920. Serial No. 348,874.

This invention relates to pressing machines, such as are used for pressing coats, trousers, or other articles of wearing apparel, or other articles or materials.

5 The object of the invention is to provide simple and improved means for enabling the two pressing members to be brought together under heavier pressure than is ordinarily secured by the effort of the operator, and more particularly to provide improved power mechanism for a press of this kind which is actuated by fluid pressure, and in which the flow of pressure for the power operation may be readily controlled.

10 15 A further object of the invention is to provide a fluid actuated power press in which the pressing members are brought together by the operator, the mechanism being so arranged that it is impossible to supply fluid pressure for the power operation unless the operator has previously brought the pressing members into pressing relation, to thereby avoid injury to the operator.

20 25 A further object of the invention is to provide an improved arrangement in which the treadle by which the operator produces relative movement between the pressing members itself controls the actuation of the power means and prevents power actuation unless the press is closed.

Further objects of the invention are in part obvious and in part will appear more in detail hereinafter.

In the drawings, which represent one suitable embodiment of the invention, Fig. 1 is a side elevation showing the press open; Fig. 2 is a sectional elevation on the line 2—2, Fig. 5; Fig. 3 is a detail sectional elevation on the line 3—3, Fig. 1; Fig. 4 is a sectional plan view on the line 4—4, Fig. 5; Fig. 5 is a detail sectional elevation on the line 5—5, Fig. 4, showing the press closed; and Fig. 6 is a sectional elevation on the line 6—6, Fig. 4.

The press shown in the drawings comprises a suitable body or frame 1 on which is supported the stationary lower pressing member or garment support 2, which may be of any of the usual or suitable forms and which preferably is a hollow member heated by steam or the like. On the frame is an upwardly extending pillar or support 3 for a swinging lever 4 one arm of which carries an upper pressing member or head 5, which may also be heated by steam or

the like, as is usual. The other arm of said lever may be provided with the usual counterweight 6, in addition to which the press may be provided with a counterbalancing 60 spring or springs 7, if desired.

The press is actuated by a pressure treadle 8 connected by an adjustable link 9 to one arm 10 of a lever pivoted in the frame, the other arm 11 of said lever co-operating 65 as a toggle member with a toggle link 12 which is connected at 13 to the point of connection between two other toggle members, one of which, marked 14, is adjustable as to length and is connected to the swinging lever and the other of which, marked 15, extends downwardly to the bed and is supported as will hereafter appear. By depressing the treadle 8 both sets of toggle members are closed, the parts moving to 70 75 the position shown in Fig. 5, in which position the head is in pressing engagement with the garment support under such pressure as is applied thereto by the foot of the operator. The parts may be locked in this 80 position by a suitable locking device, such as the hook member 16 carried by the shaft 17 and which is arranged to move into latching engagement with a pin 18 on the treadle. 19 is a counterweight for the locking member 85 and 20 a release treadle for moving said locking member to release position to open the press.

The power mechanism for producing heavy pressure between the pressing members comprises parts as follows:

Referring to Fig. 6, toggle member 15 is mounted to turn upon an eccentric 21 supported to rotate with a shaft 22. The eccentric 21 carries a projection, such as a 95 key 23, which works back and forth in an annular slot 24 of the eye portion of toggle member 15, the abrupt shoulders at the opposite ends of said slot forming abutments for co-operation with said key, as will later 100 appear. Shaft 22 is journaled in suitable bearings in the frame and is provided on its outer end with a pinion or gear segment 25 with which mesh the teeth of a rack 26 secured to or forming part of a piston rod 105 27 connected to a piston 28 working within the chamber of a cylinder 29.

The flow of pressure to and from the chamber of the power cylinder is controlled by suitable valve mechanism. The valve 110 mechanism shown in the drawings for this purpose comprises a suitably supported

valve casing 30 having a fluid pressure supply chamber 31 to which fluid pressure, such as steam is supplied by a pipe 32, the flow of pressure from said pipe to said chamber 31 being controlled by a needle valve 33. 34 represents a chamber in the valve casing which communicates with the cylinder 29 by a passage 35, while 36 represents an exhaust chamber communicating with the atmosphere through a pipe 37. In chamber 31 is a valve 38 seating downwardly toward chamber 34 and controlling the flow of pressure to said chamber 34. In chamber 34 is a similar valve 39 seating downwardly and controlling the flow of pressure from chamber 34 to chamber 36. The valve stems 40 extend outwardly from the valve casing through stuffing boxes and are pivotally connected to opposite arms of a lever 41 pivoted 10 at 42 to a bracket or support 43, one arm of said lever being pivotally connected to a block 44 slidable on a rod 45 between two compression springs 46, the pressure of which may be adjusted by screwing up the nuts 47. Said rod is connected at its lower end to one arm of an operating treadle 48 pivoted at 49 to the frame and normally held in the position shown in Fig. 5 by a tension spring 50.

30 Referring to Fig. 3, 51 represents a bracket on the frame which supports a latching member 52 provided with a latching shoulder 53 and an arm 54 extending beneath the pressure treadle 8 and normally held upwardly by the compression spring 55.

The operation is as follows:

Let us assume that the press has been closed either by hand or by depressing the pressure treadle until the parts reach the position shown in Fig. 5. By depressing the power pressure treadle 48 rod 45 is lifted, valve 38 is unseated and valve 39 is seated. Fluid pressure then flows to the cylinder, forces out the piston and through rack 26 and gear 25 turns shaft 22 and the eccentric 21 from the position shown in Fig. 6, in a counterclockwise direction until the lug 23 reaches the left hand end of slot 24.

45 The effect of eccentric 21 is to raise the lower end of the toggle member 15 and apply heavy pressure to the pressing members. By removing the foot from the treadle 48 the spring 50 turns said treadle and the valves 50 to the positions shown in Fig. 2 and the flow of fluid pressure to the cylinder is cut off and the pressure in said cylinder flows to the exhaust, but the eccentric remains in the approximately dead center position to which it has been moved. Heavy pressure between the pressing members can therefore be maintained for as long a period as desired. Quick depression and release of treadle 48 cause a puff of steam to flow to 60 the cylinder with the production of only

partial heavy pressure, in amount less than maximum according to the time the treadle 48 is held depressed. The rapidity of application of the heavy pressure can be readily varied by proper adjustments of the 70 needle valve 33, by means of which the rate of flow of fluid to the cylinder can be more or less restricted.

When the press is open or the treadle 8 is elevated spring 55 turns the latch 52 to 75 the left in Fig. 3 until its shoulder 53 lies directly beneath the power pressure treadle 48, in which position it is impossible to depress the power pressure treadle. Said treadle can only be depressed when the 80 treadle 8 has been depressed sufficiently to reach the position shown in Fig. 3 and thereby has moved the latch out of range of the downward movement of the power pressure treadle 48.

When the piston 28 is moved out by the fluid pressure behind it the lug 23 is turned to position at the left hand end of slot 24, Fig. 6. Release of pressure from the cylinder does not restore the eccentric 21 to 90 its original position. However, by depressing the release treadle 20 the tension springs 7 open the press and thereby move the toggle link 15 inwardly to the position shown in Fig. 1. The abutment at the end 95 of the slot 24 in toggle member 15 applies the turning movement of link 15 around the shaft 22 to the key or projection 23 on the eccentric 21 and thereby turns the eccentric and shaft to their initial positions and forces the piston inwardly to its original position ready for another application of fluid pressure.

What I claim is:

1. A garment press, comprising upper and lower pressing members, means for moving the upper pressing member into engagement with the lower pressing member, means for holding said pressing members in engagement, power operated means effective upon said upper pressing member and movable through a part cycle to produce final pressure between said pressing members when said pressing members are in engagement, and release means for said holding means and ineffective upon said power operated means, whereby said holding means may be released prior to the completion of the cycle of movement of said power operated means.

2. A garment press, comprising relatively movable pressing members, means for closing the press, means for holding the press closed, power operated means movable through a part cycle for producing final pressure between the pressing members when the press is closed, release means for said holding means, and means whereby opening movement of the press is effective upon said power operated means to complete its cycle of movement.

3. A garment press, comprising relatively movable pressing members, means for closing the press, means for holding the press closed, power operated means movable through a part cycle for producing final pressure between the pressing members when the press is closed, release means for said holding means, and means whereby opening movement of the press is effective upon said power operated means to complete its cycle of movement simultaneously with the opening of the press. 60
4. A garment press, comprising an upper and a lower pressing member, means for moving the upper pressing member into engagement with the lower pressing member, means for holding the pressing members in engagement, power operated means effective upon the upper pressing member and movable through a part cycle to produce final pressure between the pressing members when the press is closed, release means for said holding means, and means for effecting the completion of the cycle of movement of the power operated means during the movement of the upper pressing member out of engagement with the lower pressing member. 65
5. A garment press, comprising relatively movable pressing members, means for closing the press, means for holding the press closed, power operated means movable through a part cycle for producing final pressure between the pressing members when the press is closed, release means for said holding means, and a lost motion means effective upon said power operated means and operable by opening of the press to effect the completion of the cycle of movement of said power operated means. 70
6. A garment press, comprising relatively movable pressing members, toggle means for closing the press, means for holding the press closed, an eccentric effective upon said toggle means and movable through a part cycle to produce final pressure between the pressing members when the press is closed, release means for said holding means and ineffective upon said eccentric, whereby said holding means may be released prior to the completion of the cycle of movement of said eccentric. 75
7. A garment press, comprising relatively movable pressing members, toggle means for closing the press, means for holding the press closed, an eccentric effective upon said toggle means and movable through a part cycle to produce final pressure between the pressing members when the press is closed, release means for said holding means, and means whereby opening movement of the press is effective upon said power operated means to complete its cycle of movement simultaneously with the opening of the press. 80
8. A garment press, comprising upper and lower pressing members, means for moving the upper pressing member into engagement with the lower pressing member, power operated means effective upon said upper pressing member for producing final pressure between the pressing members when said members are in engagement, means for holding the pressing members in engagement, means for releasing said holding means, and other means for moving the upper pressing member from the position to which it has been moved by the power operated means out of engagement with the lower pressing member. 85
9. A garment press, comprising relatively movable pressing members, toggle means for closing the press, an eccentric effective upon said toggle means for producing final pressure between the pressing members when the press is closed, power means, and a rack and pinion connection between said power means and said eccentric. 90
10. A garment press, comprising relatively movable pressing members, toggle means for closing the press, operating means for said toggle means, an eccentric effective upon said toggle means for producing final pressure between the pressing members when the press is closed, a fluid pressure mechanism for operating said eccentric, valve means for controlling the operation of said fluid pressure mechanism, a treadle for operating said valve, and means operated by the toggle operating means for controlling the operation of said treadle. 95
11. A garment press, comprising relatively movable pressing members, toggle means for closing the press, operating means for said toggle means, an eccentric effective upon said toggle means for producing final pressure between the pressing members when the press is closed, a fluid pressure piston and cylinder structure, a rack and pinion connection between said piston and cylinder structure and said eccentric, valve means for controlling the operation of said piston and cylinder structure, a lever for operating said valve means, and means operated by said toggle operating means for controlling the operation of said lever. 100
- In testimony whereof I affix my signature. 105

CERTIFICATE OF CORRECTION.

Patent No. 1,640,015.

Granted August 23, 1927, to

CHARLES E. WAREAM.

It is hereby certified that the above numbered patent was erroneously issued to the inventor said "Waream" whereas said Letters Patent should have been issued by direct and mesne assignments of one-half to "The American Laundry Machinery Company, of Norwood, Ohio," a corporation of Ohio, and one-half to "United States Hoffman Machinery Corporation", a corporation of Delaware, as shown by the records of assignments in this office; and that the said Letter Patent should be read with this correction therein that the same may conform to the record of the case in the Patent Office.

Signed and sealed this 20th day of December, A. D. 1927.

Seal.

**M. J. Moore,
Acting Commissioner of Patents.**
